UNITED STATES PATENT OFFICE

158,779

ADJUSTABLE NOZZLE HAIR DRIER OR SIMILAR ARTICLE

Donald F. McCarron, St. Louis, Mo., assignor to
Knapp-Monarch Company, St. Louis, Mo., a
corporation of Delaware

Application September 24, 1949, Serial No. 5,168

Term of patent 14 years

(Cl. D86—10)

To all whom it may concern:

Be it known that I, Donald F. McCarron, a citizen of the United States and a resident of the city of St. Louis, State of Missouri, have invented a new, original, and ornamental Design for an Adjustable Nozzle Hair Drier or Similar Article, of which the following is a specification, reference being had to the accompanying drawing, forming a part thereof.

Figure 1 is a perspective view of an adjustable nozzle hair drier or similar article, showing my new design, the air discharge nozzle thereof being adjusted to an upward angle.

Figure 2 is a top plan view thereof;

Figure 3 is a side elevational view of the hair drier, showing the nozzle adjusted to a downward angle; and

Figure 4 is a front elevational view thereof.

The dominant features of my design reside in the parts of the drawing shown in solid lines.

I claim:

The ornamental design for an adjustable nozzle hair drier or similar article, substantially as shown and described.

DONALD F. McCARRON.
